UNITED STATES PATENT OFFICE.

CASPER L. REDFIELD, OF CHICAGO, ILLINOIS.

TELEPHONE-EXCHANGE.

1,185,938.

Specification of Letters Patent.

Patented June 6, 1916.

Application filed February 13, 1905. Serial No. 245,409.

To all whom it may concern:

Be it known that I, CASPER L. REDFIELD, a citizen of the United States of America, and a resident of Chicago, county of Cook, and State of Illinois, have invented certain new and useful Improvements in Telephone-Exchanges, of which the following is a specification.

My invention relates to telephone exchanges and more particularly to party line exchanges and has for its object the simplification of the mechanism and wiring of such exchanges and the arrangement of devices whereby party line exchanges may be operated without the intervention of a central telephone office.

In the accompanying drawings:—Figure 1 is a plan view of mechanism secured to the inside of the cover of a telephone box, the upper part being removed on the section line 1—1 of Fig. 3; Fig. 2 is a section on line 2—2 of Fig. 1; Fig. 3 is a section on line 3—3 of Fig. 1; Fig. 4 is a section on line 4—4 of Fig. 2; Fig. 5 is a section on line 5—5 of Fig. 2 showing the devices back of the ratchet wheel; Fig. 6 is the same as Fig. 5 with the shield or guard plate removed; Fig. 7 is a diagram showing two telephone stations connected to a party line; Fig. 8 is an additional diagram showing three stations connected together by one wire and ground.

In the said drawings B is the cover of a telephone box to the inside of which is secured a plate B¹ by means of posts B². Supported in B and B¹ is a shaft or spindle C on the outer end of which is an arm C¹. Mounted on the spindle C between the cover B and the plate B¹ is a ratchet wheel C². A pawl C⁴ pivoted at C⁵ and engaged by a spring C⁶ prevents the ratchet wheel C² from moving backward and furnishes a slight resistance to its movement in the direction of the arrow in Fig. 4.

Secured to the plate B¹ is a bracket B⁴, and secured by one end to the bracket B⁴ is a spindle D, the other end of which spindle is turned down and is guided in a socket in the spindle C, as shown in Fig. 2. Loosely mounted on the spindle D is a ratchet wheel D¹, the back face of which bears against a washer J which is held against a shoulder on the spindle D by the nut J². Between the washer J and the nut J² are a shield or guard D⁴ and a soft washer J. These

parts are so arranged that the shield is held by a slight friction between the washers J and J². The amount of this friction may be regulated by adjusting the nut J² and is normally enough to hold the shield in the place to which it is moved while at the same time offering resistance enough to prevent it from being freely moved to another position. The guard D⁴ is in the form of a sector pivoted upon the spindle D and provided with two short flanges D⁵ and D⁶ which project laterally closely adjacent to the teeth of the ratchet wheel D¹.

Supported on the plate B¹ is a polarized magnet A, whose armature A¹ is provided with a pawl A² adapted to engage and turn the wheel D¹. On a post E is a holding pawl E¹ held in contact with the wheel D¹ by the spring E². Also on the post E is a lever provided with arms F, F¹ and F². A spring F⁵ acts to turn the lever so as to move the arm F³ against an adjustable stop F⁴. In the arm F is a pin F² adapted to be engaged by a notch C⁴ in the lever C³ when the arm F³ is against the stop F⁴, but is normally held clear of the lever C³ as shown in Fig. 6.

The ratchet wheel D¹ is normally held in the position shown in Fig. 1 by a spring D⁷ shown in Fig. 3. Secured to the wheel D¹ are pins D² and D³. In the normal position of the wheel the pin D³ engages the arm F¹ to press the pin F² out of the path of the lever C³ on the spindle C, and also engages the edge of the guard D⁴ to move it so that the flanges D⁵ and D⁶ will have the relationship to the pawls E¹ and A² that is shown in Fig. 1. In this position the pawls are free to engage the teeth of the ratchet wheel D¹. When, by the action of the magnet A, the pawl A² advances the ratchet wheel, the pin D³ leaves its contact with the arm F¹ and permits the spring F⁵ to move the pin F² into the path of the arm C³ on the spindle C, thereby preventing its subsequent movement and consequently the movement of the indicating arm C¹ and the ratchet wheel C². A continued movement of the ratchet wheel D¹ results in bringing the pin D² into contact with the edge of the guard D⁴, moving it so that its flanges D⁵ and D⁶ are pushed under the pawls E¹ and A². In this position the wheel D¹ is released from its pawls and is permitted to return to its normal position under the action of the spring D⁷. Upon its

return to normal position the pin D³ strikes the guard D⁴ moving its flanges clear of the pawls so that they may reengage the wheel. It also strikes the arm F¹ moving the pin F² 5 clear of the arm C³ so that the indicating arm C¹ is again free to be moved.

On the inside face of the plate B¹ is a ring 12 provided with a series of inward projections 12^a. Insulatingly secured to the 10 ratchet wheel C² is a contact maker 13 adapted to make electrical contacts with the projections 12^a when the arm C¹ is turned. When in its normal position the contact maker 13 rests on a contact point 15 located 15 between two projections 12^a. On the outer face of the telephone box cover B is a ring B³ on which may be placed a series of numbers indicating the several stations on the party line and located in the path of the 20 arm C¹. The ratchet wheel C² and its pawl C⁴, the contact maker 13 and the projections 12^a, and the arm C¹ and the numbers of the dial ring B³ are so related to each other that the wheel and its pawl tend to stop the arm 25 C¹ at one of the numbers on the dial, and the contact maker between two projections 12^a.

Insulatingly secured to the ratchet wheel D¹ is a contact maker 24, in the path of 30 which are contact posts or points 25 and 27. The contact point 25 is located so that the contact maker 24 makes electrical connection with it when at its normal position. For different stations on the party line the 35 contact points 27 are different distances from the normal positions of the contact makers 24.

At each station in addition to the mechanism described, there is an ordinary telephone set consisting of generator G, polarized ringer Q, receiver R, hook H, transmitter T, induction coil K, batteries X and Y, and certain contact points and connections as shown in the diagrams in Fig. 7 and 8. 40 Instead of having a separate battery X at each station as shown in Fig. 8, one battery X may be used at one end of the line and an extra wire run between stations as shown in Fig. 7, or the two ways of connecting may 45 be used on the same party line as would be in the case by considering Figs. 7 and 8 two parts of the same system.

The operation is as follows:—Assuming that the subscriber at station No. 3 wishes to 55 talk with the one at station No. 5, he would turn his indicating arm C¹ to the figure 5 on his dial B, turn the crank of his generator G, remove his receiver R, talk, return the receiver, and move the indicating arm C¹ the rest of the way around to its normal position. The called subscriber does no more than remove and return his receiver.

The movement of the arm C¹ at station 60 No. 3 breaks the connection between 13 and 15, and immediately thereafter makes it

between 12 and 13, when a current flows as follows:—X—Y—12—13—14—ground at number 3 to ground at the other stations on the line 14—13—15—16—A—17—18 back to station No. 3—22—X. This is a current corresponding in direction with the polarity of the magnets A and causes them to move their respective contact makers 24 forward one step. At the next contact between 12 and 13 the movement is repeated, and as the 70 arm C¹ was moved to the number 5 on the dial the connection would be repeated five times and all of the contact makers 24 (except the one at the calling station) would be moved forward five steps. As the contact points 27 are arranged for position to correspond to the numbers given the stations, only the contact maker 24 of station No. 5 would be on its contact point 27. As the current through the magnet A goes through 80 its contact point 15, and as the connection to this point is broken at the calling station by the movement of the contact maker 13, it is evident that the contact maker at this station will not be moved but will remain in 85 connection with the contact point 25, which is connected by line 26 with point 27.

When the generator is operated the current flows as follows:—G—20—21—18 to station No. 5—22—23—24—27—28—Q—95 29—30—H—14—ground back to No. 3—14—31—G. This calls the subscriber of station No. 5 who removes his receiver, when the talking circuit is as follows: K of No. 3—33—R—34—35—H—14—ground to number 5—14—H—35—34—R—33—K—32—100 28—27—24—23—22—18 back to No. 3—22—23—24—25—26—27—28—32—K.

When the rest of the rotation of the arm C¹ is made after hanging up the receiver 105 the remaining contacts between 12 and 13 move the ratchet wheels D¹ far enough to cause the pins D² at the several stations to strike their guards D⁴ causing the release and the return of the ratchet wheels to their 110 normal position as hereinbefore described. The distance between the edge of the guard D⁴ and the pin D² which strikes it is equal in number of teeth of the wheel D¹ to the maximum number of stations that it is 115 intended to put on the party line. As the last contact between 12 and 13 represents a release of the operating mechanism and not a stop for a station, it is evident that the ring 12 would have one projection more 120 than the number of stations represented, and it may be used in that way. I may however add one or two extra contact projections, the contacts between which and the contact maker 13 would occur in the interval between the actual release of the wheel D¹ and its arrival at its normal position.

In the operating current flowing through the magnets A there are branches from 14 through H and the ringers Q, but this cur- 125

rent flows in a direction contrary to the polarity of the ringer magnets and consequently does not affect them. Likewise in the ringing circuit there are branches from 5 18 through the magnets A but the flow of the ringing circuit is contrary to the polarity of the operating magnets. In Fig. 7 the operating circuit is: X—50—22—12—etc. In Fig. 8 there are only two connections 10 between stations, ground and the wire 18. In Fig. 7 there are three connections, ground and the wires 18 and 50, the talking being through ground and 18. It will be obvious that by substituting ground connections 15 for the wire 50, and a wire for the present ground connections there would be a complete metallic circuit for talking.

It will be obvious that the present arrangement eliminates the necessity of a 20 central office and reduces the electrical devices at each station to what may be operated by a single magnet. It will also be evident that as soon as one subscriber has moved his indicating arm C¹ and has therefore 25 caused a movement of the devices at the other stations, that the pin F² of each of the stations has moved into the path of the arm C³ and consequently has locked all of the indicating arms C¹ so that they cannot be 30 moved. As a result of this no one not called on the party line can break into a connection established. Whenever it is desirable to connect the party line with some other party lines, any one of the stations on the line may 35 be selected as a central office and be supplied with a switchboard. In such a case the subscriber in that station would perform all of the functions of a central office operator while retaining the same apparatus as that 40 used at the other stations.

What I claim is:

1. The combination with a series of 45 switching mechanisms, and a propelling magnet for each, of propelling and holding devices for each mechanism, a releasing device for each adapted to be interposed between the mechanism and its propelling and hold devices, means by which each releasing device is operated by its associated 50 switching mechanism at a predetermined point in its propelled movement, and electrical connections for simultaneously operating said propelling devices.

2. A series of ratchet wheels, a magnet 55 and pawl for moving each wheel, a guard for each wheel arranged to be interposed between said wheel and its driving pawl, means for controlling said guards by the movements of their respective wheels, a contact making device adjacent to each magnet, electrical connections interconnecting the several magnets and contact making devices, and means whereby upon operating one of said contact making devices the adjacent magnet will be cut out from the elec-

trical connections while all of the other magnets will move their respective wheels and interpose their respective guards.

3. A series of switching mechanisms, a propelling magnet for each mechanism, a 70 selecting lever associated with each mechanism and normally serving to close the electrical connection of the propelling magnet therefor, means whereby the movement of selecting lever from its normal position 75 will break the electrical connection for the associated magnet and thereby prevent its operation, and means whereby such movement of the selecting lever will cause an electrical impulse to pass through all of the 80 other magnets.

4. The combination with a series of switching mechanisms, a corresponding series of propelling magnets, and a corresponding series of selecting levers, of means 85 whereby a movement of one of said selecting levers will cut out one of said propelling magnets and cause the operation of all of the other magnets of the series.

5. The combination with a series of propelling magnets, a corresponding series of selecting levers, and electrical connections for said magnets, of means whereby a movement of one of said levers will break the electrical connections of the corresponding 90 magnet and cause electrical impulses to be sent through the other magnets of the series.

6. The combination with a series of propelling magnets, a corresponding series of selecting levers, and electrical connections 100 for said magnets, of means whereby a movement of one of said levers will break the electrical connections for the corresponding magnet and cause the operation of the other magnets of the series, and means 105 whereby the operation of the other magnets will lock their corresponding levers so as to prevent their movement.

7. A switching mechanism adapted to be advanced from a normal position, devices 110 for releasing the switching mechanism so that it may return to normal position, a selecting lever, means for locking said lever so as to prevent its movement and for unlocking so as to permit its movement, a propelling magnet, and means whereby the propelling action of said magnet serves to advance and release said switching mechanism and to lock and unlock said lever.

8. In a telephone station, the combination with a switching mechanism and a selecting mechanism each of which is movable to and from a normal position, of means whereby a movement of either one of said mechanisms will prevent a movement of the 115 other mechanism until the moved mechanism has been returned to its normal position.

9. In a series of telephone stations, the combination with a selecting device and a switching device located at each station, of means 120 125 130

whereby only one of the two devices at a station may be moved at one time, and means whereby the movement of a selecting device at any one of the stations will cause a simultaneous movement of the switching devices of the other stations.

10. In a telephone station, the combination with a selecting device and a switching mechanism mounted upon a common axis, 10 of devices carried by each arranged to co-operate with the other.

11. In the switching mechanism of a local telephone station, a propelling device for moving the switching mechanism from its 15 normal position, devices for releasing the switching mechanism from its propelling device so that it may return to normal position, and means for actuating the releasing devices by the latter part of the forward movement of the switching mechanism.

12. In a telephone station, the combination with a selecting device and a switch-

ing mechanism, of an electrical connection through which said switching mechanism 25 is operated, and means by which said connection is broken by the operation of said selecting device.

13. The combination with a series of stations, a party line, and a switching mechanism at each station, of means controlled at any station for moving the switching mechanisms of the other stations so as to connect a selected one telephonically to the party line and to exclude all others, and means also 30 controlled from the same point for releasing the moved switches so as to cause them to move in a reverse direction back to their normal positions.

Signed at Chicago, Ill. this 10 day of Feb. 43 1905.

CASPER L. REDFIELD.
